CONNECTING DEVICE FOR WAVE GUIDES

Marc Jouguet, Orsay, France, assignor to Compagnie Industrielle des Telephones, Paris, France, a corporation of France

Application March 17, 1949, Serial No. 81,897
In France April 8, 1948

2 Claims. (Cl. 178—44)

1

It is well-known that waves of ultra-high frequency of the so-called (H_0) or (TE_0) type, capable of being propagated in a circular-section wave guide, have remarkable properties which render them of great advantage in practical use, on the one hand they are little affected by the slight accidental distortions of the straight sections of the guide, and on the other hand the currents which they produce in the wall of the guide are purely transversal, so that they only undergo a slight attenuation, which is the less the higher the frequency.

On the other hand, their use involves difficulties owing to the fact that they can be transmitted only in guides with linear axis, and that, consequently, they cannot go around a bend without being at least partially transformed there into waves of the type usually called (E_1) or (TM_1) except for certain particular values of the angle at which the bend causes the axis of the guide to rotate, as has been explained in British Patent 643,601, published September 20, 1950.

The object of the present invention is a device for connection between two guides of circular cross section, the axes of which have different directions without restriction which make it possible to cause a wave of type (H_0) to pass, without any perceptible loss of energy, from the first guide to the second.

The invention will be understood by reference to the following specification and the accompanying drawings, wherein:

Fig. 1 shows a section of a curved wave guide; Fig. 2 shows the orientation in space of the planes containing the several sections of guides whose assembly constitutes the connection device according to the present invention;

Figs. 3a, 3b, 3c, 3d, show illustrative examples of how to determine the structural elements of the device according to the present invention; and

Fig. 4 shows two sections which are straight and parallel but not colinear, connected by an S-shaped bent section.

Fig. 5 is a perspective view of a structural embodiment of the improved wave guide of circular cross section of the present invention, showing the several successive guide pieces assembled and the bends therein.

In order to give a better understanding of the present invention, it is necessary to recall some of the essential properties of the (H_0) and (E_1) types of waves.

(1) Let us first of all consider the case of the propagation of these waves in a linear guide.

2

(a) For a given frequency, various (H_0) waves may exist (the higher in number the higher the frequency) which correspond to the zeros of the Bessel function of the order one, normally designated by the notation, that is, the values of the argument for which $J_1=0$. Hereinafter μ_n will designate the n th non-zero root of the equation $J_1(Z)=0$. The corresponding wave is the wave (H_0, n) . All the waves (H_0) have a circular symmetry around the axis of the straight guide. The phase speed varies with the index n .

The roots of the equation $J_1(Z)=0$ for successive orders 1, 2, 3, 4 . . . n (other than the root zero) are 3.8317, 7.0156, 10.1735, 13.3237, as tabulated, for instance, on page 166 of the third (1938) edition of the Jahnke and Emde Tables of Functions. In this present specification, these successive roots are designated $\mu_1, \mu_2, \mu_3, \mu_4, \dots \mu_n$.

(b) For a given frequency, there may also be a more or less high number of waves of type (E_1) corresponding to the zeros of the equation $J_1(Z)=0$.

The n th non-zero root of the equation

$$J_1(Z)=0$$

that is at μ_n , thus also corresponds to the wave (E_1, n) . For the same frequency, the waves (H_0, n) and (E_1, n) have the same phase speed.

(c) For any wave (E_1, n) , there are two planes of symmetry passing through the axis of the straight guide. We will call these the principal plane and the anti-principal plane. They are orthogonal and are characterised by the following properties:

(1) At any point of the principal plane, the electrical field is normal to this plane, and the magnetic field is radial, i. e. directed along the intersection line of the principal plane and the right-section plane.

(2) At any point of the anti-principal plane, the electrical field is contained in this plane and the magnetic field is normal to this plane.

In the anti-principal plane there are nodal straight lines parallel to the axis of the straight guide. At any point of these straight lines the magnetic field is nil, while the electrical field is parallel to the axis of the straight guide.

(2) Let us now consider the case of propagation through a guide of which the axis is curved.

It will be assumed that this axis of the guide is contained in a plane which will be called plane Q. If a wave of type (E_1) has its principal plane perpendicular to the plane Q, it will be said that it is a wave of type (E'_1) ; if its principal plane

3

coincides with the plane Q , it will be said that it is a wave of type (E''_1, n) .

In such a curved guide, the waves (H_0, n) and (E_1, n) are replaced by three waves which, for a given frequency, have slightly different phase speeds. These three waves are:

(a) two mixed waves which will be designated $(H_0, n+E_1, n)$ and $(H_0, n-E_1, n)$ the component (E_1, n) of these waves having its principal plane merged with the plane Q . These mixed waves 10 can also be designated by the notations

$(H_0, n+E''_1, n)$ and $(H_0, n-E''_1, n)$.

(b) A wave (E_1, n) having its anti-principal plane merged with the plane Q ; it may be called 15 wave (E'_1, n) .

(3) Let us now examine the influence of a bend on the propagation of these waves.

When a guide with circular cross section has a bend, a wave (H_0, n) applied at the input end of the bend generates there the two mixed waves defined above. These waves are propagated at different phase speeds, and the result is that we get in general at the output end of the bend, a mixture of wave (H_0, n) and of wave (E_1, n) having its principal plane merged with the plane Q of the bend.

Let θ be the angle through which the bend causes the axis of the guide to rotate when passing from one end to the other of the bend. This angle is shown in Fig. 1, which represents a cross section through the plane Q of the bent guide.

In the particular case in which θ , expressed in radians, is an exact integral multiple of the angle

$$\theta_0 = \frac{\mu_n \lambda}{\sqrt{2} R} \quad (1)$$

λ being the wave length in free space and R the radius of the straight section of the guide and μ_n being the n th non-zero root of the equation $J_1(Z)=0$ as above defined, we get again entirely the wave of type (H_0, n) at the output end of the bend.

If the angle θ is a odd multiple of

$$\frac{\theta_0}{2}$$

the bend wholly transforms the wave of type (H_0, n) into wave of type (E''_1, n) .

Similarly, a wave of type (E_1, n) , having its principal plane merged with the plane Q , that is when applied to the input end of the guide, a wave of type (E'_1, n) , is, generally speaking, transformed into a mixture of wave of type (H_0, n) and of wave of type (E''_1, n) . If the angle θ is an exact integral multiple of θ_0 , the wave E'_1, n alone is found again at the output of the bend. If the angle θ is an odd multiple of

$$\frac{\theta_0}{2}$$

the wave E''_1, n is wholly transformed into wave of type (H_0, n) .

These properties being recalled, it is easy to understand the principle of operation of the device which is the object of this invention.

This device is characterised in this that it comprises, between two straight wave guides of circular cross section whose axes are in general not co-planar, and, of which the axes form any angle β between them, three guide portions C_1 , C_2 , C_3 , of circular cross-section and with curved axis, arranged one after the other and located

4

respectively in three planes Q_1 , Q_2 , Q_3 , such that the plane Q_2 is perpendicular to the plane Q_1 and the plane Q_3 is perpendicular to the plane Q_2 , the angles which the curved axes at the input and at the output ends of each of these guide portions form with respect to each other, having respectively, for the two end portions, values θ_1 and θ_3 , odd multiples of one-half of

$$\frac{\mu_n \lambda}{R \sqrt{2}}$$

radians, and, for the middle portion, a value θ_2 such that

$$\cos \theta_2 = \frac{\cos \beta \mp \sin \theta_1 \sin \theta_3}{\cos \theta_1 \cos \theta_3}$$

λ designating the wave length in free space and R being the radius of the straight portion of the guides and μ_n being the n th non-zero root of $J_1(Z)=0$ as above defined.

If the axes of the two guides are not co-planar, which is the general case, the angle β between the axes of the two guides is defined in the usual manner that $\cos \beta$ equals the sum of the paired direction cosines of the two axes.

The operation of a device of this kind will now be explained, by means of Figs. 2 and 3.

It will be assumed that in a linear guide G_1 , of which the axis is M_1M_2 (Fig. 2) a wave of type (H_0, n) is propagated. At M_2 there is connected to the guide G_1 a bend C_1 , composed of a guide with circular cross-section of which the axis is curved along an arc M_2M_3 tangential at M_2 to M_1M_2 and is situated in a plane Q_1 which contains M_1M_2 . A second bend C_2 , similar to the preceding one is connected to the bend C_1 . Its axis is curved along an arc M_3M_4 having the same 35 tangent at M_3 as the arc M_2M_3 . This arc M_3M_4 is contained in a plane Q_2 perpendicular to Q_1 and passing through the common tangent at M_3 to the arcs M_2M_3 and M_3M_4 . At M_4 a bend C_3 , similar to C_1 and to C_2 , is connected to the bend C_2 . Its axis, curved along the arc M_4M_5 has the same tangent at M_4 as the arc M_3M_4 and it is contained in the plane Q_3 led by this common tangent, perpendicular to the plane Q_2 . Finally there is connected to the bend C_3 a linear guide G_2 of which the axis M_5M_6 , tangential at 40 M_5 to the axis M_4M_5 , is contained in the plane Q_3 .

Instead of being directly connected to each other, the bends C_1 , C_2 , C_3 , may, according to the present invention, be separated by portions of linear guides. The arcs M_2M_3 , M_3M_4 , and M_4M_5 45 may be arcs of a circle or arcs of any plane curves.

θ_1 , θ_2 , θ_3 will designate respectively the values which the angle θ defined above (Fig. 1) assumes for the bends C_1 , C_2 and C_3 .

The angle formed by the direction of the axis M_5M_6 of the guide G_2 with the direction of the axis M_1M_2 of the guide G_1 has been designated by β , which guides G_1 and G_2 are the two terminal sections of guides to be joined. The value of this angle β is determined by the configuration of the system in which the guides are to be mounted, such as the location of street intersections and other obstacles, and can not be chosen arbitrarily. The value of β must be determined before the angle θ_2 can be determined. β is the angle enclosed between the parallels to M_1M_2 and M_5M_6 (Fig. 2) to which corresponds the angle $m_2O_m_5$ of Fig. 3.

It will be noted that the straight lines M_1M_2 and M_5M_6 are not generally in the same plane.

The angles θ_1 and θ_3 are, according to the invention, odd multiples of the angle.

$$\frac{\theta_0}{2}$$

defined by the Formula 1. Thus, K and K' being positive integers or zero, we will take

$$\theta_1 = \left(K + \frac{1}{2} \right) \frac{\mu_n}{\sqrt{2}} \frac{\lambda}{R} \quad \theta_3 = \left(K' + \frac{1}{2} \right) \frac{\mu_n}{\sqrt{2}} \frac{\lambda}{R} \quad (2)$$

The angle θ_2 may have any value, which, as will be seen further on, can always be chosen so that the angle has a given value.

In accordance with the properties set forth above, the wave of type (H_0, n) which is propagated in guide G_1 is transformed by the bend C_1 into a wave of type (E_1, n) assuming the plane Q_1 to be the principal plane and the plane Q_2 to be the anti-principal plane. This wave of type (E_1, n) , goes around the bend C_2 without any great change, because it is, for this bend, a wave of type (E'_1, n) . For the bend C_3 , on the other hand, it is a wave of type (E''_1, n) , and this bend transforms it entirely into wave of type (H_0, n) which is then propagated in the guide G_2 . Thus the passage of the wave of type (H_0, n) from the guide G_1 to the guide G_2 has been effected.

It is easy to calculate the angle β between the axes of guides G_1 and G_2 as a function of θ_1, θ_2 and θ_3 . It is sufficient for this purpose to consider the "indicatrix of the tangents" as hereinafter defined to the line M_1M_3 . In Figs. 3a, 3b, 3c, 3d, the indicatrix of the tangents is the curve which the point m describes when any point M describes the linear curve M_1M_6 (Fig. 2). It is possible to choose as the positive direction of the passing between M_1 and M_6 that from M_1 to M_6 . Let M be any point between M_1 and M_6 . Through a point O of the space (Fig. 3) a straight line Om is drawn parallel to the tangent at M to the line M_1M_6 ; let m be the point where this straight line intersects the sphere of center O and of radius equal to unity. When M passes from M_1 to M_6 , m describes on the spherical surface the "indicatrix of the tangents." The fixed point m_2 corresponds to the straight line M_1M_2 . The arcs (Fig. 3) of great circles $m_2m_3=\theta_1$, $m_3m_4=\theta_2$ and $m_4m_5=\theta_3$ correspond respectively to the arcs M_2M_3 , M_3M_4 , M_4M_5 of Fig. 2. The fixed point m_5 corresponds to the segment of a straight line M_5M_6 . The angle β is measured by the arc of a great circle m_2m_5 on the spherical surface.

There are two possible orientations for the bend C_2 in the plane Q_2 and two possible orientations for the bend C_3 in the plane Q_3 .

The result is that there are four possible arrangements for the three bends, and the four indicatrices of the tangents shown in Figs. 3a, 3b, 3c, 3d correspond respectively to these four arrangements. As, however, θ_1 , θ_2 , θ_3 have given values, there are only two possible values for the angle β : Figs. 3a and 3b give the same angle β_1 , and Figs. 3c and 3d the same angle β_2 . The classical formulae of spherical trigonometry give:

$$\cos \beta_1 = \cos \theta_1 \cos \theta_2 \cos \theta_3 + \sin \theta_1 \sin \theta_3 \quad (3)$$

$$\cos \beta_2 = \cos \theta_1 \cos \theta_2 \cos \theta_3 - \sin \theta_1 \sin \theta_3$$

In practice it is the angle β which is known. Thus, when the particular values given by Formulae 2 have been chosen for θ_1 and θ_3 , it is possible to determine by means of Formula 3 the value of the angle θ_2 of the central bend of the connecting device according to the present invention.

Thus we have:

$$\cos \theta_2 = \frac{\cos \beta_1 + \sin \theta_1 \sin \theta_3}{\cos \theta_1 \cos \theta_3} \quad (4)$$

5 The sign which must be taken in this formula is determined by the following rule:

Let an observer be placed standing on the sphere of unit radius of the indicatrix and looking in the direction of the tangents. The indicatrix sphere is the sphere of unit radius on which are traced the indicatrices of the tangents. At m_3 and m_4 it rotates through an angle of 90° . If it effects this rotation twice in the same direction (case of Figs. 3a and 3b) the sign — in Formula 4 must be taken. In the contrary case (that of Figs. 3c and 3d) the plus sign must be taken.

The positive or zero integral numbers K and K' being chosen, Formula 4 gives θ_2 , provided that $\cos \theta_2$ be comprised between -1 and $+1$. There is always at least one solution; there can be two.

An example will now be given, as an indication of the values assumed, in a particular case, by the angles defined by the bends of the connecting device according to the present invention.

It will be assumed that it is desired to transmit a wave $(H_0, 1)$. We then have $\mu_n = \mu_1$ and the Formula 1 becomes:

$$\theta_0 = 155 \frac{\lambda}{R} \text{ degrees} \quad (5)$$

It will also be assumed that the ratio λ/R is equal to $1/5$; the Formula 5 then gives:

$$\theta_0 = 31 \text{ degrees}$$

35 If we assume $K = K' = 0$, the Formulae 2 give

$$\theta_1 = \theta_3 = 15.5 \text{ degrees}$$

For $\beta = 20^\circ$, the Formula 4 gives only one solution corresponding to the sign — (arrangement of Figs. 3a and 3b):

$$\theta_2 = 16.2 \text{ degrees}$$

For $\beta = 40^\circ$, it gives two solutions:

$$\theta_2 = 62.7 \text{ degrees}$$

45 and

$$\theta_2 = 51.5 \text{ degrees}$$

The first corresponds to the arrangements of Figs. 3a and 3b, the second to those of Figs. 3c and 3d.

55 It may be well, in practice, to subject the axis of the guide G_2 to a given translation d . This is particularly the case if it be desired that the axes of G_1 and G_2 should be in the same plane. In order to obtain this result, it is possible, in accordance with the present invention, to insert in the device, at any point whatsoever, an S-shaped guide such as that shown in Fig. 4. As the axis has parallel directions at the input and output of this S-shaped guide, the latter in no way interferes with the operation of the device.

60 What I claim is:

1. A device for connecting two rectilinear wave guides of circular cross section, said guides being such that the axis of the first guide makes an angle β with a line which is parallel to the axis of the second guide and which crosses the axis of the first guide, said device being so constructed that a wave of the H_0 or TE_0 type which is being propagated in a first one of said guides passes without sensible loss of energy into the second said guide, said two wave guides being prolonged by a first length of curved guide and a second length of curved guide forming arcs the central

angles of which are respectively θ_1 and θ_3 which are odd multiples of

$$\frac{\mu_n \lambda}{2R\sqrt{2}}$$

where μ_n is the n th non-zero root of the Bessel J_1 function according to the Jahnke and Emde tables, and λ is the wave length in free space, and R is the radius of the cross section of the guides, said device being characterized by the fact that it comprises between said first and second lengths of curved guide, an intermediate third length of curved guide forming an arc having a central angle θ_2 such that

$$\cos \theta_2 = \frac{\cos \beta \sin \theta_1 \sin \theta_3}{\cos \theta_1 \cos \theta_3}$$

whose curved axis is situated in a plane Q_2 perpendicular to the planes Q_1 and Q_3 of the curved axes of said first and second lengths of curved guide, so that the first said length transforms the H_0 wave into an E_1 wave, and that the intermediate said third length of curved guide transmits the E_1 wave substantially without attenuation, and that said second length of curved guide transforms the E_1 wave into a H_0 wave.

2. A device for connecting two rectilinear wave guides of circular cross-section which are adapted to convey ultra-high frequency electromagnetic wave energy, said wave guides being such that the axis of the first guide makes an angle β with a line which is parallel to the axis of the second guide and which crosses the axis of the first guide, comprising a first curved guide and a

second curved guide constituting, respectively, prolongations of said two rectilinear wave guides, said first and second curved guides forming arcs the central angles of which are respectively θ_1 and θ_3 , said angles being multiples of, respectively, angles θ_1 and θ_3 which angles are odd multiples of

$$\frac{\mu_n \lambda}{2R\sqrt{2}}$$

where μ_n is the n th non-zero value of the Bessel function J_1 and λ is the wave length in free space of the transmitted wave, and R is the radius of the cross section of said guides, said device further comprising interposed between said first and second curved guides, an intermediate third curved forming an arc the central angle θ_2 of which is such that

$$\cos \theta_2 = \frac{\cos \beta \sin \theta_1 \sin \theta_3}{\cos \theta_1 \cos \theta_3}$$

and whose curved axis lies in a plane Q_2 perpendicular to the planes Q_1 and Q_3 of the curved axes of said first and second curved guides respectively.
